CURVE DRAWING INSTRUMENT

Filed Dec. 26, 1928

Fig. 3.

Charles F. Weidman,
INVENTOR

P. O. Hickey.

WITNESS:

BY Victor J. Evans

ATTORNEY

UNITED STATES PATENT OFFICE

CHARLES F. WEIDMAN, OF VICKSBURG, MISSISSIPPI

CURVE-DRAWING INSTRUMENT

Application filed December 26, 1928. Serial No. 328,377.

This invention relates to measuring instruments of the geometrical type.

An object of the invention comprehends the provision and arrangement of means forming curves of different degrees.

Another object of the invention contemplates a guide for the curve forming means to predetermine the degree thereof.

An additional object of the invention consists in the provision of a support for the guide whereby the curve forming means will not become distorted while in use.

A further object of the invention comprises a second guide arm attached to the center of the flexible member having connection with the body of the instrument to prevent bulging of the flexible element when the latter is shifted to occupy different positions.

With the above and other objects in view, the invention further consists of the following novel features and details of construction, to be hereinafter more fully described, illustrated in the accompanying drawing and pointed out in the appended claims.

25 In the drawings:—

Figure 1 is an elevation of my invention shown extended to capacity.

Figure 2 is a view similar to Figure 1 illustrating the retracted position of the flexible element.

Figure 3 is a detail sectional view taken on line 3-3 of Figure 1.

Referring to the drawing in detail, where in like characters of reference denote corresponding parts, the reference character 10 indicates generally the body portion of the drawing instrument, which can be constructed of wood, metal, xylonite, or any other suitable material.

40 A curved arm or flexible element 11, extended from one end of the body portion of the instrument, is formed of steel, celluloid, xylonite, etc.

45 A guide arm 13, formed upon the free end of the flexible element 11, the outermost edge of which 12 forms a tangent to the curved flexible member 11 at the point of curvature X. Said guide arm 13 being adapted to slide within a groove or raceway 14 in the body of 50 the instrument having under cut grooves 15.

in the side walls thereof and in communication with the raceway bottom, the purpose of which will be presently apparent. Fins 16, laterally projecting from the side edges of the guide arm 13, are adapted for reception within the undercut grooves 15 to prevent displacement of the guide arm 13 therein as manifest from the illustration of my invention in Figure 3 of the drawing. The adjacent outer surfaces of the body of the instrument proper and the guide arm 13 are calibrated to indicate the radii of segments of circles or curves capable of being drawn by the present type of instruments. 55 60

A slotted arm 17, having a stud 18 horizontally disposed within one end, is adapted to be projected within a slot 19 in the body of the instrument 10. A slot 19 of curved formation is located adjacent the raceway 14. The opposite end of the slotted member or arm 17 is carried upon the shank 20 of a knurled adjusting screw 21, which also retains the guide arm 13 in any desired position. A guide arm, such as indicated at 22, is provided with a pin 23, right angularly disposed within the innermost end and projecting through the elongated longitudinally disposed slot 24 in the member 17 and a channel 25 in the body portion of the instrument. 65 70 75 80

A head 26, carried upon the outermost end 80 of the guide arm 22, is bifurcated upon the outer end to provide a curved channel 27 to accommodate the inner side of the flexible element 11. The guide arm 22 is primarily adapted to prevent irregularities in the flexible element 11 when same is shifted to occupy its respective positions. The slide features for the guide arms 13 and 22 and the slotted member 17 coact in such manner that the fulcrum point for the guide arm 22 changes 85 as the radius of the circle is increased or diminished commensurate with the regulation of the guide arm 13.

With the present invention, true arcs can be drawn without determining the center of the circle. The radius can be quickly adjusted, thus replacing compasses and beam compasses for curves of short radii and the customary sets of railroad curves for curves of longer radii.

It is obviously apparent that the flexible element is to be used as a guide for pen or pencil.

The invention is susceptible of various changes in its form proportions and minor details of construction, and the right is herein reserved to make such changes as properly fall within the scope of the appended claims.

Having described the invention, what is

claimed is:—

1. A drawing instrument comprising a body, a curved flexible element fixed at one end to the body, a guide arm projected from the free end of the element, the body having a raceway in the face thereof within which the said guide arm is slidably mounted, fins formed upon the side edges of the guide arm adapted for reception within undercut grooves at the sides of the raceway, a slotted member having one end pivoted on the guide arm and the other end slidably mounted within a slot disposed beyond one end of the raceway, and an adjusting element passed through the meeting portions of the guide arm and slotted member to retain the flexible element in adjusted position.

2. A drawing instrument comprising a body, a flexible element fixed at one end to the body and terminating at its free end in a guide arm, the body being provided with an arcuate-shaped raceway having undercut grooves in the walls thereof in which said guide arm is slidably mounted, side fins carried by the guide arm slidably mounted within the grooves, a slotted member pivotally connected with the guide arm having the opposed end thereof slidably connected with a slot within the body beyond one end of the raceway, a second guide arm slidably mounted upon the slotted member and the body of the instrument, and a head included upon the outermost end of the second guide arm bifurcated to accommodate the adjacent portion of the flexible element.

3. A drawing instrument comprising a body, a curved elongated flexible member fixed at one end to the body and terminating at its free end in a guide arm, the body being provided with an arcuate-shaped raceway having undercut grooves in the side walls thereof in which is mounted the said guide arm, side fins carried by the guide arm slidably mounted within the grooves, a slotted member pivotally connected within a slot in the body, a second guide arm slidably mounted upon the slotted member and the body of the instrument, a head included upon the outermost end of the second mentioned guide arm bifurcated to accommodate the adjacent portion of the flexible element, and a securing element having connection with the meeting portions of the guide arm and the slotted member.

In testimony whereof I affix my signature.

65 CHAS. F. WEIDMAN.
